(57) **CLAIM**

The ornamental design for the hummingbird feeder reservoir, as shown and described.

DESCRIPTION

FIG. 1 is a front perspective view of the hummingbird feeder reservoir, showing our new design, the broken lines representing environment and forming no part of the claimed design;

FIG. 2 is a right perspective view of one of the reservoirs for a hummingbird feeder shown separately for clarity of disclosure, the broken lines representing environment and forming no part of the claimed design;

FIG. 3 is a right front perspective view of one of the hummingbird feeder reservoir illustrated in FIG. 2;

FIG. 4 is a top plan view of the hummingbird feeder reservoir illustrated in FIG. 2;

FIG. 5 is a bottom plan view of the hummingbird feeder reservoir illustrated in FIG. 2;

FIG. 6 is a front elevation view of the hummingbird feeder reservoir illustrated in FIG. 2;

FIG. 7 is a right elevation view of the hummingbird feeder reservoir illustrated in FIG. 2;

FIG. 8 is a rear elevation view of the humming bird feeder reservoir shown in FIG. 2; and,

FIG. 9 is a left elevation view of the hummingbird feeder reservoir shown in FIG. 3.
